UNITED STATES PATENT OFFICE

WILLIAM DUGUID AND HENRY ROLFE, OF WINNIPEG, MANITOBA, CANADA

GOLF-BAG STAND

Application filed September 24, 1928; Serial No. 307,905, and in Canada August 13, 1928.

The invention relates to improvements in golf bag stands and an object of the invention is to provide means for supporting a golf or caddy bag in a substantially upright position so that the bag does not have to be thrown down on the ground during the interval that the player is making a shot and which also supports the bag so that the player can readily select and replace a club without the necessity of stooping down or lifting the bag.

A further object is to construct a device which can be readily attached to the existing forms of golf bags without materially altering the structure thereof.

A further object is to provide a device embodying two legs which can be expanded to form with the bag a tripod support to retain the bag in a substantially upstanding position and wherein the collapsing movement of the legs towards the bag may be brought about by a lifting movement of the bag handle or of the suspensory strap customarily employed for carrying the bag from the shoulder.

A further object is to construct the device in a simple, durable and inexpensive manner and so that there will be no undue flapping movement of the legs when the bag is being carried.

With the above more important objects in view, the invention consists essentially in the arrangement and construction of parts hereinafter more particularly described, reference being had to the accompanying drawings, in which:

Fig. 1 is a side view of a golf bag equipped with my invention and showing the legs extended to support the bag in a substantially upright position.

Fig. 2 is a perspective view of the device, the golf bag having been removed.

Fig. 3 is an enlarged detailed vertical sectional view through the upper end of the bag and the attachment, the section passing centrally and vertically through the handle.

Fig. 4 is a perspective view of the hinge block employed.

Fig. 5 is a perspective view of the spring.

Fig. 6 is a sectional view similar to Figure 3 but showing a modified arrangement.

Fig. 7 is a sectional view similar to Figure 6 and showing a still further modified arrangement.

Fig. 8 is a plan view of the parts appearing in Figure 7.

In the drawings like characters of reference indicate corresponding parts in the several figures.

The golf or caddy bag 1 may be of canvas or any suitable material and it is herein shown as bound at the top with a leather 2 reinforced in the usual manner and as having the bottom 3 closed in the ordinary way.

The device which we provide is fastened to the bag and embodies a top circular band 4 adapted to enter the upper end of the bag and to which we fasten permanently a pair of diametrically opposing, downwardly extending bars 5 and 6 which have their lower ends connected by a cross member 7, the cross member resting on the bottom of the bag and the side bars 5 and 6 being contained within the sides of the bag. None of the latter parts are exposed at the outside of the bag.

In locations at ninety degrees away from the bars, we attach to the band a pair of diametrically opposing pivot pins 8 and 9 which protrude through the part 2 and pivotally support an upper spanner member 10 in the form of a rod which has the ends thereof down turned at the forward side of the bag and terminating in opposing eyes 11 and 12. The rear side of the spanner member inclines downwardly from the pivot pins, it being desirable that no part of the spanner member project beyond the top of the bag at any time.

A pair of spaced rivets or bolts 13 and 14 are carried by the rear bar 5 and project through the bag and slidably support the handle 15. The handle is herein shown as formed from a piece of bar iron bent in the shape shown best in Figure 3 and having the outer semicircular portion 16 thereof forming a hand grip and the inner flat portion 17 forming an attaching bar.

The attaching bar is longitudinally slotted as indicated at 18 and 19 to receive the rivets, the arrangement being such that the handle

100

can be moved up and down in respect to the bag. The handle has a loop 20 formed at its upper end and the loop receives rotatably the spanner member, the arrangement being such that the down movement of the handle in respect to the bag swings the eyes 11 and 12 in a direction upwardly and away from the front side of the bag, the spanner bar swiveling on the pivots 8 and 9. The customary suspending strap 21 is fastened also in any suitable manner to the upper end of the handle and has the lower end thereof fastened to the bag body and accordingly when one lifts either on the handle or on the strap, the up movement so occasioned swings the eyes 11 and 12 inwardly and downwardly towards the bag.

To the front side of the bar 6, we permanently fasten a bearing block 22, this block being outside the bag, the material of which passes between the block and the bar as will be readily understood. The block is provided with two vertically disposed, inwardly converging slots 23 and 24 and these slots receive the upper ends of a pair of similar legs 25 and 26, the legs being pivotally attached to the block by similar pivot pins 27 crossing the slots. The legs are of a length such that when extended as best shown in Figures 1 and 2, they are spread and form with the bag a tripod supporting the bag in the substantially upright position shown. A lifting bar 28 is pivotally connected to the leg 25 and to the eye 12 and a similar lifting bar 29 is pivotally connected to the leg 26 and to the eye 11.

It is desirable that the legs be prevented from flapping when the bag is being carried about and accordingly means is provided for pressing them towards the bag and holding them normally in contact with the bag.

The means herein shown embodies a plate 30 fastened to the block and providing extending spring arms 31 and 32 engaging the front sides of the upper ends of the legs. Whilst we have shown this particular spring structure, it will be readily understood that spring pressure could be brought to bear on other portions of the working parts to press the legs normally towards and hold the same in contact with the bag. The legs will naturally gravitate to a position against the bag when the bag is lifted and held in a substantially vertical position but the springs insure that there will be no undesirable flapping of the legs.

When a golf bag is supplied with this device, it will be readily seen that when the same is being carried about by the handle or the suspending strap, the weight of the bag will cause it to maintain a down position in respect to the handle with the result that the legs will be held folded in against the lower part of the bag. When one desires to make a shot, the bottom of the bag is placed on the ground and the handle is then shoved down.

As it goes down, the legs are drawn out and spread and form with the bag a tripod supporting it in the manner best shown in Figure 2. When the shot is finished, one simply grasps the handle or the shoulder strap and lifts the same and this automatically causes the infolding of the legs.

In Figure 6, we have shown a modified form of the invention. Here the handle 15 is indicated as permanently fastened to the bar 5 and the suspensory strap as permanently fastened to the upper end of the golf bag and the spanner member 10 has been provided with a thumb piece 33 overlying the handle. With this arrangement, the handle is grasped in the usual manner by the fingers and a down pressure of the thumb on the thumb piece will cause the extending movement of the legs.

In Figure 7, we have shown a further modification and in this the handle, instead of being slidably attached to the bar 5, is mounted for an up and down swinging movement. In this case, the device is provided with the upper band 4 and a lower band 4' and the spanner member 10 is carried by the lower band and the band 4 carries pivotally a semi-circular bail bar 10'. The bail bar 10' and the spanner bar 10 are then connected by the handle 15 so that they swing together as will be readily understood. The supporting strap, is attached in any suitable manner to the upper end of the handle.

The various structures shown all embody a spanner member, legs and lifting bars between the spanner member and the legs and the only differences between them otherwise is in the manner in which the spanner member is actuated.

What we claim as our invention is:—

1. In a golf bag support, a pair of tripod legs pivotally attached centrally to the front side of the bag and foldable against the bag, a spanner member encircling the upper end of the bag and pivotally supported from the sides thereof, downwardly extending front lifting means connecting the spanner member with the legs and a rear handle vertically slidable in relation to the bag and attached to the rear part of the spanner member.

2. In a golf bag support, a supporting structure insertible within the bag, a pair of pivoted tripod legs exterior of the bag and fastened to the structure, a member spanning the upper end of the bag and pivotally attached to the supporting structure and lifting members pivotally connecting the spanner member with the legs.

3. In a golf bag support, a supporting structure insertible within the bag, a pair of pivoted tripod legs exterior of the bag and fastened to the structure, a member spanning the upper end of the bag and pivotally attached to the supporting structure, lifting members pivotally connecting the spanner member with the legs and a handle at the ex-

terior of the bag and carried by the supporting structure and positioned adjoining the spanner member at the side of the bag remote from the legs.

5. 4. In a golf bag support, a supporting structure insertible within the bag, a pair of tripod legs located outside the bag at the front and pivotally supported from the supporting structure, a member spanning the 10 upper end of the bag and pivotally attached to the supporting structure and having the ends thereof overlying the legs, lifting members pivotally connecting the latter ends of the spanner member with the legs and a 15 handle located at the rear side of the bag and carried by the supporting structure and located adjacent the rear side of the spanner member.

5. In a golf bag support, an upper band 20 contained within the upper end of the bag, a pair of diametrically opposing front and rear supporting bars fastened to the band and extending downwardly into the bag, a bearing block permanently fastened through 25 the bag to the front bar, a pair of tripod legs pivotally attached to the bearing block, a member spanning the upper end of the bag and having the ends thereof located above the legs and the sides thereof pivotally mounted 30 on pivot pins extending from the sides of the band through the sides of the bag, lifting arms pivotally connecting the ends of the spanner member with the legs and a handle carried by the rear bar and vertically slid- 35 able in respect to the bag, said handle being attached to the rear side of the spanner member.

Signed at Winnipeg, this 24th day of August, 1928.

40 WILLIAM DUGUID.
HENRY ROLFE.
